UNITED STATES PATENT OFFICE

EDWIN R. GILL, JR., OF YONKERS, NEW YORK, ASSIGNOR TO PRISMO HOLDING CORPORATION, A CORPORATION OF NEW YORK

SIGN

Application filed January 15, 1932. Serial No. 586,827.

The invention relates to signs when that term is used in its broadest aspect and includes any marker, signal device or mechanism which may be employed to attract attention or convey information. Little difficulty has been found in producing devices of this character which will be substantial, relatively cheap, more or less permanent and satisfactory for use in the day time or under ordinary lighting conditions. While the present invention is adapted for such use, it is more especially adapted to meet the unusual conditions which have not been satisfactorily met up to the present time.

In order that such a device be satisfactory in all places and under any circumstances it is highly desirable that it be especially responsive to light thrown upon it and this is especially desirable when the device or its surroundings may be in the dark.

It is well known that a sign provided with a reflecting surface may be illuminated and to some extent made visible in the dark. Ordinarily reflecting surfaces throw out light at an angle opposite to that at which the light is received so that their visibility is not high from the direction of the source of light. Such a reflecting sign is not satisfactory for use, for instance, as a roadside sign where ordinarily the light of a vehicle on the road reaches the sign at an angle and where it is highly desirable that the light be reflected back to the vehicle. Attempts have been made to improve such signs by providing light dispersion or light diffusion means on the signs so that when illuminated they glow to some extent and throw out light in all directions. Such an arrangement obviously is uneconomical and may let so little light go toward its source as to be unsatisfactory. The intensity of the light returned toward the source in a way determines the visibility of the sign. If the intensity of the returned light can be increased, the distance at which the sign may be visible or legible can be increased. In present times when motor cars using roads habitually operate at high speeds, it is highly desirable that signs be visible for great distances and this is especially important at night when characteristics of the road

itself may not be perceived much in advance of the approach of the vehicle. One purpose of the present invention is to produce a sign for such use as well as other uses.

It has been discovered that if a sign or the significant portion thereof is not merely reflecting but is reflex reflecting the light thrown thereon will to a considerable extent be returned toward the source of the light. A single reflex reflecting medium in order to be of material use must be large. It is expensive to make, difficult to protect and likely to be removed, injured or destroyed. It has been found that a brilliant reflex reflection may be procured by providing a number of small reflex reflecting elements which are preferably arranged substantially in contact with each other so as to avoid the appearance of blind or dark spots.

It has been found that small, regularly shaped pieces of transparent material such as glass, preferably in the form of spheres, cubes or cylinders whose height equals the diameter and the like, may be conveniently employed for this purpose especially when associated with a reflecting medium, and the present invention is based at least in part upon this idea.

In order to explain fully the invention, the accompanying drawings have been prepared in which Figure 1 is a face plan view of a fragment of a sign embodying the invention. Fig. 2 is a vertical transverse fragmentary section through a portion thereof. Fig. 3 is a fragmentary plan view of an optional arrangement. Figs. 4, 5 and 6 are sectional views of details. Fig. 7 is a diagrammatic illustration showing the effect of light upon a sign embodying the invention. Fig. 8 is a face plan view of one form the invention may take. Fig. 9 is a transverse vertical section of Fig. 8. Figs. 10, 11, 12, 13, 14, 15 and 16 are detail views of optional arrangements.

A sign may consist of a rigid base or back 20 which in practical use will preferably be a sheet of metal. On this, for its protection, may be a layer of enamel 21 which may be reflecting and may be cloudy, clear or color-

less but preferably will be colored. Insignia or indicating devices 22 may be marked out on the layer 21 or may consist of a separate and preferably contrastingly colored enamel inset or overlaid thereon. Substantially covering the insignia 22 are provided reflex reflecting elements 23 which may be spheres, cubes or other regularly shaped geometrical devices and which preferably may be clear, transparent, colorless glass. As indicated in Fig. 2 the spheres 23 will each be embedded in the enamel preferably to substantially one half the depth of the sphere. Such embedding insures the spheres being permanently held in place. It will be remembered that the enamel is reflecting and when the sphere is properly embedded therein there is produced a reflex reflecting medium of such character that substantially any ray of light falling upon it will be reflected back in a line parallel to the approaching light. For instance, the ray A of Fig. 5 passing diametrically through the center of the sphere 23 will be reflected directly back upon its own path. The ray B in approaching on a diameter will be refracted and reflected back upon the line B¹ which is parallel to and in the same direction as the line B. Likewise the ray C will be reflected back upon the parallel line C¹ and the ray D will be reflected back upon the parallel line D¹. It will be apparent that in order to produce a reflex reflection at a considerable angle to the face 22 of the sign the reflecting medium 21 should cover nearly the lower half of the sphere which correspondingly should be embedded in the reflecting enamel layer 21 to the extent of substantially one half of its diameter or possibly somewhat less since if, for instance, the incoming ray D did not meet a reflecting surface at the point E it would tend to pass through the sphere and out and there might be little or substantially no light returned along the path D¹. It will be clear that the maximum distance between an entering ray such as B and its reflex reflected ray B¹ will be something less than the diameter of the sphere so that the most advantageous arrangement for the reflex reflection of the light may be by the use of a very small reflex reflecting elements 23. As a practical matter it may be found convenient to employ spheres of clear glass which may be somewhat less than $\frac{1}{2}$ of an inch in diameter. One advantage of using such very small spheres is that when they are properly positioned, more or less closely in contact with each other, only very small and very inconsiderable spaces may be left between them. Thus no blind, black or dead spaces may appear in the reflex reflecting area. Another advantage of the small elements is that they may be readily embedded a sufficient distance in the enamel layer 21 and the amount they project therefrom will be so small as to not

produce a materially irregular surface, thus leaving little opportunity for the accumulation of dirt to foul or blind the sign and at the same time leaving very little projecting matter to be cracked or broken off to destroy or deform the reflex reflecting elements. While there is a material advantage in using small reflex reflecting elements their use is not essential to all phases of the invention.

To make the device a practical satisfactory reflex reflecting sign or signal it is desirable that the small glass spheres be as small as possible so as to form a multiplicity of lights as each sphere, regardless of size, is comparatively inefficient in itself and a great number of these lights are required to furnish the requisite illumination. A single bead is hardly discernible. Large sized balls would leave many dark dead spots which may not be distinguishable if a multiplicity of minute beads are employed.

While the reflex reflecting elements embedded in the enamel may be stable and not subject to undesirable results from exposure to the elements, etc. they may be left uncoated. It may, however, be desirable under some circumstances to place a protective covering or coating on the elements or on the sign as a whole. In Fig. 5 such a coating 24 is illustrated. This may consist of a layer of enamel, varnish or the like. In order not to interfere with the efficiency of the sign it should be transparent and it may be colorless, although if it is colored it will cause its color to be carried by the reflexly reflected rays of light.

While for some purposes it may be sufficient to have the enamel layer 21 and the reflex reflecting elements 23 and the layer 24 colorless any one or more of these three elements may be colored and so produce a corresponding colored effect in the reflected rays of light. While the insignia are shown on a base 21, it is obvious that the base might be omitted and the insignia alone employed. Likewise as illustrated in Fig. 3 the insignia 22 may be omitted or left blank and the reflex reflecting elements 23 applied to the main surface or back of the sign. For some purposes in order to emphasize the presence of the sign or the insignia or to produce other effects, portions of the base, in addition to the insignia, may be provided with reflex reflecting elements 23 as indicated in the lower transverse strip 25 in Fig. 1. A transparency may be placed before such a solid field.

As indicated in Fig. 5, the optical structure of the sphere 23 is such that the reflex reflected ray B¹ is further from the parallel diameter A of the sphere than the incoming ray B. In Fig. 6 is illustrated a reflex reflecting element which will have less tendency to spread the rays and will produce an outgoing ray F¹ which is an equal distance from the parallel diameter G as the incoming ray

F. Such a structure may be made up of two hemispheres 26 and 27 which may be constructed by calculating the focal length of the curve of the surface of the hemisphere 26 and 5 then describing the hemisphere 27 having a diameter equal to the focal length of 26. While such a form might be the ideal reflex reflecting element to employ, from a practical commercial standpoint it may be difficult 10 and expensive to manufacture and also difficult and expensive to properly place and embed in the enamel layer. The small diameter of the spheres actually used may approach very closely to the theoretical ideal indicated 15 in Fig. 6 since as the sphere gets smaller the difference in diameter between 26 and 27 becomes less.

The characteristics of a sign made in accordance with the present invention may be 20 indicated by such an arrangement as is illustrated in Fig. 7 in which a sign 20 may be mounted upon a vertical wall 28 with which is associated a wall 29 at right angles. Light thrown from the source 30 will reflect from 25 the plain enamel portion 21 of the sign 20 and illuminate the wall 29 at the area 21B. Likewise light from the source 30 will reflect from the enamel portion 21A and illuminate the area 21C on the wall 29. Light, 30 however, from the source 30 striking the reflex reflecting elements 23 on the sign 20 will be returned substantially to the source 30, substantially none of the light being reflected to the area 23A on the wall 29. The result 35 will be that an image of the sign will appear on the wall 29, the portion corresponding to the reflecting enamel surface 21 being bright and the portion corresponding to the reflex reflection portion 23 being dead or blank. 40 This may be taken as an indication that substantially all of the light falling upon the reflex reflecting surface 23 is returned toward the source of light.

While the description above has referred 45 to single rays of light, it is understood that ordinarily light travels, not as a single ray, but as a pencil of rays which is more or less conical in shape. Consequently the actual operation of the sign is not actually represented by the ray phenomena indicated and 50 described but will more or less closely approach that operation in general.

It must be understood that due to lack of 55 theoretically perfect transparency, reflection and refraction and due to the use of colors, a certain small amount of spreading of the beam cannot be prevented especially when commercial glass must be employed for practical purposes. In other words, the beam 60 from the moment it is refracted into (or enters) the reflexing crystal will begin to cone out and the reflected beam will leave the crystal not at a point without area but as an oval or circle with more or less actual 65 although minute diameter. The lines in the

70 drawing representing reflected beams therefore really delineate the axes of truncated cones of light. This is not diffusion in a true sense. Diffusion as generally employed contemplates reflecting and refracting a mass of incident light heterogeneous in all directions at once but this is foreign to the present invention.

The reflex refraction of the impinging light, substantially all of which is returned toward the source, is to be clearly distinguished from the usual opposite reflection of a plane surface and the general diffused glow of the usual rough heterogeneous surface. 75

80 With the invention thus described before him one versed in the art will have no difficulty in manufacturing a sign. The metal sheet may have applied to it the coating to make the enamel layer 21. A cut-out of the 85 insignia desired, preferably made of thin material, may then be placed upon the material and the reflex reflecting elements 23 scattered thereon. The reflex reflecting elements may be embedded the proper distance 90 in the enamel material by hand or by running a roller or the like thereover and then the surplus loose elements may be brushed off. It is highly desirable that the reflex reflecting elements be placed as close together as 95 possible and that there be but a single layer of them. This may be accomplished in any suitable way. The prepared sign may then be baked and the reflex reflecting elements 100 into the enamel by which process they will 105 be rigidly and permanently held in place. When desired the enamel for that portion of the sign other than the insignia may be separately baked as preliminary step or a second layer of enamel for the insignia may 110 be applied after the first baking.

115 Since the shape of the under side of the reflex reflecting elements, that is that side toward the base plate 20 or embedded in the enamel 21 or the like, is important to carry out the functions hereof, it is desirable that the heat used to bake or finish the enamel be not high enough to melt or deform the spheres or the like used. To this end it may 120 be desirable to use for the reflex reflecting element some such material as glass having a relatively high melting point and associate it with a coating or enamel having a lower melting point for baking. Thus it may be 125 possible and usual in practice to set or embed the glass spheres or the like in the materials of which the main covering coat is to be made and then subject the entire sign to a temperature sufficiently high to melt, bake and finish the enamel without melting or deforming the glass reflex reflecting elements. A heat high enough to deform the reflex reflecting elements or to allow them to run into each other or become welded together may 130

interfere with the efficiency of the device and decrease or limit the light effectively reflected. The baking may be done in one or more steps.

5 In general any binder may be used which fulfills the requirements of the invention, that is, it should be light reflecting, not absorbing, and it should not be transparent nor objectionably translucent. It should be also 10 able to stand up under the anticipated conditions of use. For outdoor work, of course, resistance to weather is essential. This gives a wide choice of materials and variations available. Pottery, concrete, wood plastic, 15 cellulose solutions, glue, colodion etc. are not desirable nor are most varnishes, lacquers, etc. except for coating the final surface.

It may be desired to have the general surface of the sign of dull, dead or not reflecting material or it may be desired to have the reflex reflecting elements on the surface or only slightly embedded therein. In Fig. 4 is illustrated an arrangement in which the back 20 may be provided with a suitable coating 21D. To this may be affixed, or in this 25 may be embedded, a plurality of reflex reflecting elements 23 which have previously been silvered or coated with a layer of reflecting material 31 such as mercury or other 30 bright metal. Such a coated reflex reflecting element is shown toward the bottom of Fig. 4. When the elements have been fixed in place on the back or on the layer 21D, they 35 may be rubbed, polished or treated in any other way to remove the reflecting layer 31 from their outer sides leaving the reflecting coating only on substantially half their inner sides as indicated at the upper part of Fig. 4. This figure is intended to be a fragmentary illustration of two of the reflex reflecting elements in place on a sign during 40 the process of manufacture in which the reflecting coating 31 of the upper one of the elements is removed and that of the lower 45 one is about to be removed. In Fig. 4 a space is indicated between the two reflex reflecting elements 23 for purposes of clearness of illustration. In practice a space may exist if 50 the two elements are in different insignia on a sign but if they are in the same insignia the space preferably will be reduced to a minimum and elements 23 will be in substantial contact with each other.

55 The glass reflex elements may be coated with mercury or "silvered". They may then be dipped with a paint solution similar to the protective coating on the back of mirrors, or the "silvered" surfaces can be copper 60 plated instead of painted. A sign being laid out on any suitable back plate the coated reflex agents are then affixed in an orderly layer to those parts of the sign which it is intended to render luminous, by any sort of 65 enamel, glue, paste, cement, or adhesive

whatsoever consistent with the anticipated usage and duration of the sign. The enamel, adhesive or cement can be transparent or non-transparent, reflecting or non-reflecting in this form, the qualities of permanence and resistance to deterioration only being considered. The mercury coating in this case is the reflecting agent.

70 Another way of constructing my sign or signal is to partially embed the glass reflex elements in a layer of solder, or preferably an alloy, such as type metal, that expands on cooling for binding. In this case spheres or reflex elements may be embedded to about half their diameter in the alloy layer. A 75 metal back plate is used to which the alloy adheres and acts as retaining and reflecting element for the reflexing elements.

80 Another method is to use reflex elements, "silvered" and copper plated as described above and to sweat these onto a back plate 85 and then clean the silver off the face as indicated above.

85 Instead of "silvering" the reflex crystals they can be coated with flake metal paint, such as the common aluminum paint or the so-called "gold paint" of flake brass.

90 Figs. 8 and 9 show a sign similar to Figs. 1 and 2 in which instead of the spherical reflex reflecting elements 23, reflex reflecting 95 elements 32 in the shape of cubes are used and they may be applied as are the spheres in the previous figures. In Fig. 9 is shown the base 20 on which is a complete layer of 100 enamel or the like 21 upon which has been placed a second layer of enamel or the like 21E in the form only of the insignia desired and on this are affixed or embedded the reflex reflecting elements 32. An ideal arrangement of the cubes over a surface in perfectly regular ranks and files is illustrated. 105 This may not be attained in commercial work but in practice the layout of the cubes will be an approximation of this ideal as closely as practicable.

110 That the majority of the light rays falling upon a cube will be reflexly reflected is indicated in Figs. 10, 12, 13 and 14. In Fig. 10 is illustrated a ray H approaching the cube 115 at the point h. This is reflected from the point i to the point k to the point l and goes out at the point m in the line H¹ parallel to the incoming ray H. A ray K indicated in Fig. 12 normal to the surface of cube 32 returns on its own path. A ray L at such a 120 small angle to the surface of the cube 32 that it does not meet a side of the cube is reflected from the base of the cube along the line L¹ at something of an angle to the incoming ray L and rays of this character will be somewhat diffused. A ray M, however, striking the cube at a slight angle but near enough to a side wall to be affected thereby will return along the line M¹ substantially parallel 125 to the incoming ray M. Likewise rays N, O, 130

P and Q illustrated in Figs. 13 and 14 will be refracted and reflected to return along the lines N¹, O¹, P¹, Q¹, parallel to the incoming rays and this will be so whether the cubes 5 are set flatly on their bases or tipped to a slight extent as indicated in Fig. 14 or actually fall and rest on a corner as illustrated in Fig. 11. As illustrated in Figs. 11, 12 and 14, the cubes 32 will preferably be substantially 10 embedded in the reflecting enamel 21. Since the sides of the cubes perform important functions in the reflection, it is highly desirable that they be enclosed in the reflecting enamel.

15 As indicated in Fig. 13 the enamel or other coating if it is transparent and colorless may entirely cover and enclose the cubes 32 giving additional protection and possibly with only slightly reduced efficiency. In Fig. 14 is illustrated a coating of colorless transparent enamel, varnish or the like 24A corresponding to the coating 24 of Fig. 5.

Fig. 16 shows an arrangement of cubes corresponding to the arrangement of spheres 25 in Fig. 4. Each cube 32 may be covered with a coating of a reflecting material 31A and after they have been put in place the exposed surfaces may be cleaned of the reflecting material. As in Fig. 4 the elements 30 have been shown separated but they may be in contact.

The reflex reflecting elements may consist of various regular geometrical forms each being used separately or mixed with others. 35 In addition to the spheres and cubes described in detail above, there is illustrated in Fig. 15 a cylinder which preferably will have its diameter equal to its height. As illustrated, substantially any rays striking it 40 at an angle will be reflexly reflected when it is embedded in a layer of reflecting enamel 21.

The legibility of the sign is very high. 45 As there is no concentrated glare the message it is intended to convey can be read at a great distance; much further than the present sign using comparatively few lenses of large size to dot out cymbals, letters and figures.

50 The luminous sign being hardly more costly than any ordinary non-luminous sign can be used extensively, adequately, or even profusely, as circumstances in each case may 55 require without burdening the taxpayers of the community unduly and thereby giving the authorities of our states, counties, and municipalities a free hand to promote the safety of the American motoring public by 60 adequate warnings and directions plainly visible at all hours of the day or night. Night traffic on our highways, especially at intersections, and congested centers, is one of the great hazards of the American citizen.

65 A road fully posted with luminous signs and

signals would remove a great part of the danger and therefore the present invention will confer an incalculable benefit to society.

Variations from the exact things here 70 shown and described may be made in many ways as the invention is not confined to specific details.

I claim as my invention:

1. A sign the significant portion of which 75 is covered with a plurality of reflex reflecting elements, and a reflecting substance covering at least about the lower half of the surfaces of the elements but leaving the upper portions of the surfaces unaffected.

2. The method of making a sign comprising applying a layer of unbaked enamel to a base, embedding a layer of glass spheres in the enamel to at least about one half their depth, and baking at a temperature which 80 will melt and fix the enamel and cause it to adhere to the spheres without affecting their shape.

3. The method of making a reflex reflecting surface comprising substantially completely coating a plurality of reflex reflecting elements with a reflecting coating, affixing said elements to a base, and removing the exposed reflecting coating.

4. A sign comprising a base and insignia, 90 a reflecting coating on the base and a reflex reflecting coating on the insignia made up of a plurality of substantially contacting minute reflex reflecting elements each provided with a reflecting back throughout substantially its lower half.

5. A sign comprising a rigid base, a layer 95 of reflecting fused enamel on at least the significant portion thereof and small, substantially contacting clear glass spheres in a substantially single layer embedded into the enamel on the significant portion of the sign, the fusing temperatures of the spheres being somewhat above that of the enamel.

6. A sign a significant portion of which 110 is covered with a plurality of substantially symmetrical reflex reflecting elements each of which is less in its largest dimension than the smallest dimension of the significant portion of the sign and each of which is internally reflecting to about half its depth on the side toward the sign.

7. In a sign a portion covered with a reflecting layer and a plurality of relatively small substantially symmetrical reflex reflecting elements embedded to about half their depth in the reflecting layer.

8. In a sign a portion covered with a reflecting layer and a plurality of relatively small substantially symmetrical reflex reflecting elements embedded to about half their depth in the reflecting layer so as to seal the contacting surface of the elements and the layer from the weather.

9. A one-piece sign comprising a base of 130

a metallic plate, a coating of fused reflecting enamel therein, having a plurality of relatively small substantially symmetrical and substantially contacting reflex reflecting units embedded in at least a portion of the enamel to about one half their depths.
